UNITED STATES PATENT OFFICE

HARRY ZIMMERMAN, OF TORONTO, ONTARIO, CANADA, ASSIGNOR TO BEULAH BELLE ZIMMERMAN, OF TORONTO, ONTARIO, CANADA

BUFFING WHEEL BLANK PLIES

Application filed September 25, 1930. Serial No. 484,461.

My invention relates to improvements in methods for cutting buffing wheel blank plies from lengths of material, and is particularly directed towards the type of blank from which a pleated regular hexagon shaped buffing wheel ply is formed.

In this type of blank as shown in United States Letters Patent No. 1,669,224, May 8th, 1928, to Frank Yerges, the blank is of elongated form, cut on the bias in respect to the weave and folded into parallel pleats so that the resultant form of ply is substantially circular.

The object of my present invention is to form the blanks of such a shape that they are complementary to each other, in that there is no waste of material between adjacent blanks when they are laid out upon the length of material from which they are cut.

A further object of my invention is to so position the blanks in relation to the length of material from which they are cut that the sides of the material length pass through the blanks, whereby partial blanks are formed, such partial blanks being joined together to form whole blanks.

A still further and particular object of my invention is to form my blanks of a plurality of substantially identical hexagonal figures each having two opposite parallel sides of the same length as the sides of the regular pleated hexagon forming the ply, and the other four sides equal to each other, and of greater length than the sides of the hexagon ply.

My invention consists of a method for cutting blanks all as hereinafter more particularly described and illustrated in the accompanying drawing in which:-

Fig. 1 illustrates a length of material having large sized hexagonal blanks formed therein, wherein no wastage of material occurs between the complementary blanks.

Fig. 2 is a similar view to Fig. 1, the material having small sized hexagonal blanks formed therein.

Fig. 3 illustrates a length of material having octagonal blanks formed therein and from which pleated octagonal buff blanks can be made, such figure however showing the

wastage of material which occurs in the cutting of octagonal blanks.

Fig. 4 illustrates a hexagonal blank formed by joining two partial blank portions, and

Fig. 5 illustrates a pleated hexagonal ply 55 formed from a blank similar to that shown in Fig. 4.

Like characters of reference indicate corresponding parts in the different views in the drawing.

Referring first to Fig. 3 wherein octagonal blanks 1 are shown in relation to a length of material 2 from which they are cut, it will be clearly seen that these blanks 1 cannot be positioned in any way complementary to each other, so that there is no wastage of material between the blanks, there being in fact a large waste of material 3 in proportion to the area of the blanks. This type of blank is of course integral and can be formed into a 70 pleated ply of octagon form.

In my invention as illustrated in Figs. 1, 2, 4 and 5 I show the use of blanks of hexagonal form, the blanks 4 illustrated in Fig. 1 being of greater length than the diagonal 75 width of the length of material 5 across which they extend so that the blanks are cut from the material in the form of partial blanks, the partial blanks being joined together to form complete blanks such as illustrated in Fig. 4.

In laying out blanks in relation to the length of material for the production of blanks which are on the bias to the weave, I place two blanks, for example, 4^A and 4^B end 85 to end, and lay such blanks in diagonal relation to the width of material so that the longitudinal center line X passing through the blanks from edge to edge of the material is equal to the length of a complete blank. 90 By this method the portions 4^A and 4^B will of course make a complete hexagonal blank upon being joined together. The other blanks complementary to the blanks 4^A and 4^B are also complementary to each other, and 95 when the end to end portions are joined together will form complete blanks, for example, when the portion 4^C is secured to the end of the partial blank 4^D a complete hexagonal blank will be formed.

Upon further reference to Fig. 1 it will be seen that in cutting the blanks of hexagonal form and in accordance with my method that there is absolutely no wastage of material between the complementary blanks, and that the only wastage in the material length will be at the ends which of course may be very far apart, wherein a certain wastage must occur, as of course there is not sufficient material at these points to permit the forming of partial blanks of the same size as the blanks throughout the length of material. These waste portions can however be used for making smaller sized blanks.

It will of course be appreciated that in many cases it is advantageous to produce comparatively small blanks 8 from material of the same width as the material illustrated in Fig. 1, and in such a case as illustrated in Fig. 2 the blanks can be so laid out upon the material that instead of the edges of the material passing through two blanks which are laid end to end, that it is possible to have a central integral blank 8^a and two partial blanks 8^b and 8^c extending from the ends of the integral blank. In laying out these blanks as illustrated in Fig. 2 I place the integral blank 8 and the partial blanks 8^b and 8^c in diagonal relation to the width of the material so that the longitudinal central line Y passing through the blanks from edge to edge of the material is equal to the length of two complete blanks. The other blanks are complementary to the blanks 8^a 8^b and 8^c and are also complementary to each other, and when the portions bounded by the edges of the material are joined together will form complete hexagonal blanks.

The partial blanks are sewn or otherwise secured together as illustrated in Fig. 4, and are then pleated into the form illustrated in Fig. 5. The sides of the blank illustrated in Fig. 4 being of course the sides of the blank illustrated in Fig. 5 after such blank is pleated.

It will be apparent in the use of my particular method for cutting blanks of the form described that I need only use material of a standard width from which blanks of any desired size may be cut, thus obviating the necessity of stocking materials of different widths for the manufacture of different sized blanks. It will of course be also understood that after the blanks are pleated and sewn that the centers or arbours are punched therein and the peripheries and blanks cut into circular form.

From the foregoing description it will be apparent that I have devised an extremely effective method of cutting blanks of the character described from lengths of material wherein no wastage of material between the complementary blanks occurs, and although I have shown and described my blanks as set in a particular relation to the length of

material from which they are cut it is to be understood that my type of blanks can be laid out upon the material in any desired direction other than the diagonal direction shown without departing from the spirit of my invention which contemplates the use of a hexagonal blank and the laying out of such blanks upon the length of material in complementary blank form.

What I claim as my invention is:

1. A blank for a pleated buffering wheel ply of regular hexagon form, comprising a hexagonal piece of material having all its angles obtuse angles, two sides of which are the same length as the sides of the regular hexagon pleated blank and the other four sides of which are equal to each other and of greater length than the sides of the regular hexagon and adapted to be shortened by the pleats.

2. A method of forming a buffering wheel ply of a plurality of equal blanks of elongated hexagon form, comprising the cutting out of the blanks by a plurality of cuts, each cut forming an edge of each of two adjacent blanks, some of the blanks being complete and some of the blanks incomplete where they are bounded by the edges of the material from which the blanks are cut, joining the complementary portions of incomplete blanks to form complete blanks, pleating the complete blanks crosswise of their length so that they are reduced to substantially regular hexagon form, and laying a plurality of such pleated blanks together to form the buffering wheel ply.

3. A method of forming a buffering wheel ply of a plurality of equal blanks of elongated hexagon form, in which two sides are equal and the other four sides equal to each other and of greater length than the two sides, comprising the cutting out of the blanks by a plurality of cuts, each cut forming an edge of each of two adjacent blanks, some of the blanks being complete and some of the blanks incomplete where they are bounded by the edges of the material from which the blanks are cut, joining the complementary portions of incomplete blanks to form complete blanks, pleating the complete blanks crosswise of their length so that they are reduced to substantially regular hexagon form, and laying a plurality of such pleated blanks together to form the buffering wheel ply.

4. A buffering wheel ply of substantially regular hexagon shape formed of pleated material and in which the pleats lie substantially parallel to a line extending from corner to corner of the hexagon and through the centre thereof.

HARRY ZIMMERMAN.
